ABSTRACT

A new and distinct cultivar of *Coreopsis* plant named 'Baluptowed', characterized by its semi-double type, bright yellow-colored inflorescences having a medium-sized, burgundy-red colored eye zone, medium green-colored foliage, and moderately vigorous, mounded growth habit, is disclosed.

1 Drawing Sheet

1

Latin name of genus and species of plant claimed: *Coreopsis* hybrid.

Variety denomination: 'Baluptowed'.

BACKGROUND OF THE INVENTION

The present invention relates to a new and distinct cultivar of *Coreopsis* plant botanically known as *Coreopsis* hybrid and hereinafter referred to by the cultivar name 'Baluptowed'.

The new cultivar originated in a controlled breeding program in Santa Paula, Calif. during July 2013. The objective of the breeding program was the development of *Coreopsis* cultivars having large inflorescences, substantially continuous blooming throughout the summer, and mounded growth habits.

The new *Coreopsis* cultivar is the result of cross-pollination. The female (seed) parent of the new cultivar is the proprietary *Coreopsis* hybrid breeding selection coded 17822-1, not patented, characterized by its single-type, light yellow-colored inflorescences having a large, dark burgundy-colored eye zone, dark green-colored foliage, and moderately vigorous, upright growth habit. The male (pollen) parent of the new cultivar is the proprietary *Coreopsis* hybrid breeding selection coded 17832-1, not patented, characterized by its semi-double-type, medium gold-colored inflorescences having a small, medium red-colored eye zone, medium green-colored foliage, and moderately vigorous, compact-mounded growth habit. The new cultivar was discovered and selected as a single flowering plant within

2

the progeny of the above stated cross-pollination during May 2014 in a controlled environment in Santa Paula, Calif.

Asexual reproduction of the new cultivar by terminal stem cuttings since May 2014 in Santa Paula, Calif. and Elburn, Ill. has demonstrated that the new cultivar reproduces true to type with all of the characteristics, as herein described, firmly fixed and retained through successive generations of such asexual propagation.

SUMMARY OF THE INVENTION

The following characteristics of the new cultivar have been repeatedly observed and can be used to distinguish 'Baluptowed' as a new and distinct cultivar of *Coreopsis* plant:

1. Semi-double type, bright yellow-colored inflorescences having a medium-sized, burgundy-red colored eye zone;
2. Medium green-colored foliage; and
3. Moderately vigorous, mounded growth habit.

Plants of the new cultivar differ from plants of the female parent primarily in having a different flower form, smaller sized inflorescences, lighter colored foliage, and a different growth habit. Plants of the new cultivar differ from plants of the male parent primarily in having a different flower color, and a larger burgundy-colored eye zone.

Of the many commercially available *Coreopsis* cultivars, the most similar in comparison to the new cultivar is the *Coreopsis* cultivar BIG BANG 'Cosmic Eye', U.S. Plant

Pat. No. 22,601. However, in comparison, plants of the new cultivar differ from plants of 'Cosmic Eye' in at least the following characteristics:

1. Plants of the new cultivar have more ray florets than plants of 'Cosmic Eye';
2. Plants of the new cultivar are taller and wider than plants of 'Cosmic Eye'; and
3. Plants of the new cultivar have larger diameter inflorescences than plants of 'Cosmic Eye'.

BRIEF DESCRIPTION OF THE PHOTOGRAPHS

The accompanying photographs show, as nearly true as it is reasonably possible to make the same in color illustrations of this type, typical flower and foliage characteristics of the new cultivar. Colors in the photographs differ slightly from the color values cited in the detailed description, which accurately describes the colors of 'Baluptowed'. The plants were approximately 16-weeks old and grown in one-gallon containers in Elburn, Ill. Plants were given one pinch prior to transplant and one pinch two weeks after transplant.

FIG. 1 illustrates a side view of the overall growth and flowering habit of 'Baluptowed'.

FIG. 2 illustrates a close-up view of an inflorescence of 'Baluptowed'.

DETAILED BOTANICAL DESCRIPTION

The new cultivar has not been observed under all possible environmental conditions to date. Accordingly, it is possible that the phenotype may vary somewhat with variations in the environment, such as temperature, light intensity, and day length, without, however, any variance in genotype.

The chart used in the identification of colors described herein is The R.H.S. Colour Chart of The Royal Horticultural Society, London, England, 2015 edition, except where general color terms of ordinary significance are used. The color values were determined in June 2016 under natural light conditions in West Chicago, Ill.

The following descriptions and measurements describe 16-week old plants produced from cuttings from stock plants and grown under conditions comparable to those used in commercial practice. Rooted cuttings were transplanted into one-gallon containers and were given one pinch prior to transplant, and then one pinch two weeks after transplant. Seven weeks after transplant plants were grown outside in Elburn, Ill. Greenhouse temperatures were maintained at approximately 65° F. to 70° F. (18.3° C. to 21.1° C.) during the day and approximately 55° F. to 60° F. (12.8° C. to 15.6° C.) during the night. No supplemental lighting was provided. Measurements and numerical values represent averages of typical plants.

Botanical classification: *Coreopsis* hybrid cultivar Baluptowed.

Parentage:

Female parent.—Proprietary *Coreopsis* hybrid breeding selection coded 17822-1, not patented.

Male parent.—Proprietary *Coreopsis grandiflora* breeding selection coded 17832-1, not patented.

Propagation:

Type cutting.—Terminal stem.

Time to initiate roots.—Approximately 10 to 12 days at 70° F. (21° C.).

Time to produce a rooted cutting.—Approximately 5 to 6 weeks at 70° F. (21° C.).

Root description.—Fibrous, thin, white in color.

Rooting habit.—Freely branching, dense.

Plant description:

Commercial crop time.—Approximately 10 to 12 weeks from a rooted cutting to finish in a one-gallon container.

Growth habit and general appearance.—Herbaceous perennial, moderate growth vigor, compact-mounded growth habit.

Hardiness.—USDA zones 5 to 9.

Size.—Height from soil level to top of plant plane: Approximately 36.0 cm. Width: Approximately 35.0 cm.

Branching habit.—Freely branching, pinching improves basal branching. Quantity of lateral branches per plant: 8 main branches each having approximately 4 lateral branches.

Main branches.—Strength: Moderately strong. Length to base of peduncle: Approximately 12.0 cm. Diameter: Approximately 3.0 mm. Length of central internode: Approximately 5.0 cm. Texture: Slightly glossy, glabrous. Color of young and mature stems: 144A.

Foliage description:

General description.—Quantity of leaves per main branch: Approximately 4. Type: Simple and trifoliate. Fragrance: None. Arrangement: Opposite. Aspect: Petiole is acute angle to stem; blade is somewhat perpendicular to stem. Shape of leaf and leaflet: Elliptic. Margin of leaf and leaflet: Entire, ciliate. Apex of leaf and leaflet: Acute. Base of leaf and leaflet: Attenuate, simple leaf sessile. Venation pattern: Pinnate.

Simple leaf.—Length: Approximately 10.0 cm. Width: Approximately 2.7 cm. Texture of upper and lower surfaces: Sparsely pubescent. Color of upper surface of young and mature foliage: 137A with indistinguishable venation except for midvein of 146B. Color of lower surface of young and mature foliage: Closest to between 138A and 138B with indistinguishable venation except for midvein of 146B.

Mature trifoliate leaf.—Length of mature trifoliate leaf: Approximately 10.0 cm. Width of mature trifoliate leaf: Approximately 7.0 to 9.0 cm. Length of terminal leaflet: Approximately 9.5 cm. Width of terminal leaflet: Approximately 2.3 cm. Length of lateral leaflet: Approximately 3.5 to 4.5 cm. Width of lateral leaflet: Approximately 1.0 cm. Texture of upper and lower surfaces: Sparsely pubescent. Color of upper surface of young and mature foliage: 137A with indistinguishable venation except for midvein of 146B. Color of lower surface of young and mature foliage: Closest to between 138A and 138B with indistinguishable venation except for midvein of 146B. Length of petiole of mature trifoliate leaf: Approximately 3.0 cm. Diameter of petiole of mature trifoliate leaf: Approximately 2.0 mm. Texture of petiole of mature trifoliate leaf: Sparsely pubescent. Color of upper and lower surfaces of petiole of mature trifoliate leaf: 146B.

Flowering description:

Flowering habit.—'Baluptowed' is freely flowering under outdoor growing conditions with substantially continuous blooming from spring through autumn.

Lastingness of individual inflorescence on the plant.—Approximately 7 to 10 days.

Inflorescence description:

General description.—Type: Daisy-type composite, actinomorphic. Persistent. Shape: Round. Aspect: Erect. Arrangement: Terminal capitulum, positioned above the foliage. Quantity per plant: Approximately 15. Diameter: Approximately 5.8 cm. Depth: Approximately 2.5 cm. Fragrance: Slightly acrid.

Peduncle.—Strength: Strong, flexible. Aspect: Erect. Length: Approximately 12 cm to 14 cm. Diameter: Approximately 2.0 mm. Texture: Glabrous, slightly glossy. Color: 144A.

Bud.—Rate of opening: Generally takes 4 to 5 days for bud to progress from first color to fully open inflorescence. Quantity per plant: Approximately 32.

Bud just before opening.—Shape: Ovoid. Width: Approximately 1.1 cm. Depth: Approximately 1.0 cm. Color: 152B to 152C.

Ray florets.—Quantity per inflorescence: Approximately 16. Arrangement: In two whorls, imbricate. Aspect: Flattened to slightly twisted. Shape: Obovate. Margin: Entire. Apex: Incised. Base: Rounded. Length: Approximately 2.4 cm. Width: Approximately 1.3 to 1.5 cm. Texture of upper and lower surfaces: Glabrous, abaxially ribbed. Color of upper surface when first open: 6A with base of 187A. Color of lower surface when first open: 6B with an underlay of 187B at base. Color of upper surface when fully open: 5A with base of 187A. Color of lower surface when fully open: 5B with an underlay of 187B at base.

Disc florets.—Quantity per inflorescence: Approximately 130. Arrangement: Massed in center of inflorescence. Shape: Tubular, approximately lower 90% fused. Margin: Entire. Apex: Five acute tips. Base: Fused. Length: Approximately 1.0 cm. Diameter at tube opening: Approximately 3.0 mm. Diameter at base: Approximately 1.0 mm. Texture of outer surface: Glabrous. Texture of inner surface: Glabrous with glandular pubescence on tips. Color of upper or inner surface when first and fully open: Closest to 154D, translucent with tips of 17A. Color of lower or outer surface when fully open: Closest to 154D, translucent with tips of 17B.

Disc.—Diameter: Approximately 1.7 cm. Depth: Approximately 8.0 mm.

Receptacle.—Shape: Dome. Height: Approximately 3.0 mm. Diameter at base: Approximately 5.0 mm. Color: 145D.

Phyllaries.—Quantity per inflorescence Approximately 16. Arrangement: In two equally divided whorls. Base of inner whorl fused into cup-shaped base surrounding receptacle, non-imbricate, held close to ray florets.

Outer phyllaries.—Shape: Lanceolate. Margin: Entire, ciliate. Apex: Acute. Base: Truncate. Length: Approximately 1.0 cm. Width: Approximately 3.0 mm. Texture of upper and lower surfaces: Glabrous, glossy. Color of upper and lower surfaces: 137A.

Inner phyllaries.—Shape of free portion: Ovate. Margin: Entire. Apex: Acute. Base: Fused. Length: Approximately 9.0 mm. Width: Approximately 6.0 mm. Texture of upper and lower surfaces: Glabrous. Color of upper and lower surfaces: 152D with cup-shaped portion of closest to 144B.

Reproductive organs.—Androecium: Present on disc florets only. Stamen quantity: 5. Stamen length: Approximately 6.0 mm. Filament length: Approximately 3.0 mm. Filament color: 154D. Anther shape: Oblong, basifixied. Anther length: Approximately 3.0 mm. Anther color: 154D, translucent, tinted with 187A. Pollen amount: Abundant. Pollen color: 17A. Gynoecium: Present on disc florets only. Pistil quantity: 1 per floret. Pistil length: Approximately 1.0 cm. Stigma shape: 2-branched. Stigma length: Each branch approximately 2.0 mm. Stigma color: 17B. Style length: Approximately 7.0 mm. Style color: 154D. Ovary length: Approximately 2.0 mm. Ovary color: 145D.

35 Seed and fruit production: Neither seed nor fruit production has been observed.

Disease and pest resistance: Resistance to pathogens and pests common to *Coreopsis* has not been observed.

What is claimed is:

40 1. A new and distinct cultivar of *Coreopsis* plant named 'Baluptowed', substantially as herein illustrated and described.
